GAUGING DEVICE

Willis Fay Aller, Dayton, Ohio, assignor to The Sheffield Corporation, Dayton, Ohio, a corporation of Ohio

Application January 21, 1950, Serial No. 139,891

5 Claims. (Cl. 101—43)

1

This invention relates to gauging apparatus and more particularly to apparatus for gauging different dimensions of an article and marking the gauged classification according to the gauged sizes.

One object of the invention is to provide a gauging apparatus having a series of marking means each provided with different characters indicative of different article dimensions with provision for simultaneously and automatically applying the proper marks to the article in accordance with the gauging results.

Another object is the provision of a gauging apparatus having means for moving articles successively to a gauging station in which each article is gauged by a plurality of gauging heads that are movable from normally retracted positions to article engaging positions, such gauging heads providing gauging means for automatically selecting the positions of marking devices and with provision for automatically applying the marks to the articles in accordance with the sizes gauged.

Another object is the provision of a gauging apparatus of the character mentioned in which the marking devices are operated by weights or hammers to indent the indicia of the marking means into the article.

Another object is the provision of a gauging apparatus for selecting sizes in three or more classifications with provision for setting gauging switches providing for such classifications by means of only a maximum and a minimum master.

Another object is the provision of a gauging apparatus for gauging the sizes of bores in a block and adapted to conveniently place the block in gauging position and automatically carry out a gauging cycle in which the sizes of the bores are applied to the block.

In the particular adaptation of the invention herein disclosed the gauging apparatus provides a loading position in which a cylinder block may be placed. The normal gauging and classification cycle is then initiated automatically. A hydraulic ram carries the block into gauging position against a positive stop and a hydraulically actuated locating pin then locates the block in gauging position. Having been located, gauging heads which measure the sizes of the cylinder bores by measurement of the amount of air leakage between gauging nozzles in these heads and the surfaces of the cylinder bores are then automatically lowered into gauging position. If interference is encountered the descent of the gaug-

2

ing heads is stopped automatically. Having lowered the gauging heads to a predetermined depth the gauging and selecting sequences are started and during gauging sequence the gauging heads operate in conjunction with electric switches and selecting mechanism which control stamping devices. The selectors set up and hold the proper classification of the stamping mechanism. If all bores are within tolerance individual counters for each of the several classifications are actuated and indicate the number of pistons required for each corresponding classification so that the proper piston stock can be built up for assembly. The size classification of the cylinder bores are automatically stamped on the cylinder block adjacent each bore. Having been stamped, the gauging heads are all retracted simultaneously and the selecting devices operate to normal position. The block locating means are retracted leaving the block free to be pushed on through the machine as the next block is brought into gauging position.

Setting and calibration of the gauging device is made by means of maximum and minimum master setting rings mounted in fixed position so that a gauging head can be withdrawn into one or the other of these setting rings for setup purposes, and provision is also made for setting the electric switches that provide, for example, five classifications of cylinder bore size merely by maximum and minimum masters and a calibrated pressure responsive device instead of requiring five different masters, one for each size classification.

With the above and other objects in view as will be more apparent from the following specification and the appended claims, reference is made to the accompanying drawings in which,

Fig. 1 is a plan view of a gauging apparatus embodying the present invention, portions being broken away to show certain features of the block feeding and locating mechanism;

Figs. 13a, 13b and 13c together show the electrical connection or wiring diagram; and

Fig. 14 is a chart of the classifications accomplished by the gauging switches.

Referring more particularly to the drawing in which the same reference numerals are supplied to like parts in the several views, the gauging apparatus in the particular embodiment herein illustrated is adapted to gauge the eight cylinder bores of a cylinder block and provide for five different size classifications in the acceptable size range. Obviously the invention is applicable to other uses and it will be understood that the number of size classifications may be more or less than the figure chosen for exemplary purposes.

The apparatus comprises a main support or frame 10 having an article receiving stand or plate 11 on which the cylinder block to be gauged may be placed. Tracks 12 flush with the upper surface of the plate 11 extend rearwardly into the gauging apparatus and between the tracks 12 is a guide bar 13 which may be received in the longitudinal groove of the cylinder block, the block itself being indicated in Fig. 1 at 14 and shown in dot and dash lines in Fig. 2 where it is in gauging position inside the main housing. The cylinder block is moved from its position on the plate 11 by means of a ram 15 which pivotally carries a bifurcated lever 16 on shaft 17. The ram 15 is guided on a stationary horizontal bar 18 and one end of the lever 16 is pivotally connected by means of a pin 19 to the end 20 of a piston rod 21 which operates in a long fluid pressure cylinder 22. When oil or other hydraulic fluid is supplied to one end of the cylinder 22 the piston rod 21 is ejected so as to move the lever 16 counterclockwise to a limited extent determined by abutments 23 on the feed block, thus first retracting the outer end of the arm 16 from the cylinder block and then picking up the ram 15 and moving it into position for engagement with a cylinder block on the plate 11. As fluid under pressure is supplied to the other end of the cylinder 22, a pull is first applied to the shorter end of the lever 16 to move the longer end of the lever out ready to pick up the cylinder block and as the piston 21 continues to move, the ram 15 and the arm 16 move together and shove the cylinder block into gauging position as shown in Fig. 1. Just before the cylinder block reaches gauging position, a cam surface 25 on the ram 15 engages a roller 26 on the end of a pivoted lever 27 carried by the main frame and moves that lever clockwise against the action of a spring 28 so as to project a stop toe fixed on the other end of the lever 27 into the path of travel of the cylinder block and stop the movement of the cylinder block at the proper point in its feeding travel. Just before the cylinder block reaches the stop toe 29 it also engages and operates a

4

switch controlling lever 30 carried by the lever 27 to control a switch 154 which controls a valve governing the supply of hydraulic fluid to a fluid pressure cylinder 35 (see Fig. 2) so that a bell crank lever 36 is moved counterclockwise into the position shown in Fig. 2 and projects a locating pin 37 into a hole provided at the proper place in the cylinder block to properly locate the cylinder block in exact gauging position.

10 Promptly after this occurs a hydraulically controlled clamping ram 38 is lowered against the top of the block to assist in holding the block firmly in its located position.

The apparatus is provided at each side with 15 four gauging heads which are normally in a raised or retracted position but which are lowered after the block is in gauging position so as to enter the four cylinder bores 39 on each side of an eight-cylinder engine block. One of these

20 gauging heads is shown at 40 in Fig. 2 and another at 41 in Fig. 2, and although the head 41 is lowered as shown in the drawing for illustrative purposes it should be understood that in normal operation all of the gauging heads are 25 moved downwardly or upwardly at the same time. The gauging heads are arranged on carrying bars 42 guided in sleeves 43 and normally held in a projected position with respect to the sleeve by means of springs 44. The four sleeves 43 at

30 one side of the apparatus are carried by a slide 45 which is guided on the frame structure 46 and movable thereon by means of a pair of hydraulic cylinders 47 and piston rods 48. By supplying fluid to the upper ends of the hydraulic cylinders 47 the gauging heads may be lowered into the cylinder bores and by reversing the fluid supply they can be moved outwardly to a normally retracted position. The slide 45 has a rack at

35 each end meshing with a pair of speed gears 49 which are fixed to a common shaft 50 to provide a force balance that prevents slide 45 from binding or cocking in its guideways. The four gauging heads at the opposite side of the apparatus are similarly mounted and controlled.

45 It will be understood that each gauging head, such as the gauging head 40, is provided with a pair of opposed fluid leakage nozzles 52 connected to an internal passage or tube extending along the rod 42 and to a pressure gauge or other

50 suitable flow measuring device such as the gauge 53 one of which is provided for each gauging head. A further explanation of the actual gauging operation will be given in connection with the switch controls that are operated by each gauging 55 head in order to energize one of a series of circuits according to which particular one of the five classifications in the tolerance range of acceptable sizes corresponds to the particular cylinder bore gauged. In accordance with the selected contact of a particular cylinder bore gauging device there is an automatic control of a marking or stamping mechanism which applies the proper indicia to the cylinder block adjacent the cylinder bore gauged.

60 A marking mechanism as shown in Figs. 2 and 4 to 9 inclusive is provided for each gauging head. Each of these mechanisms has a series of characters of indicia such as numbers 1, 2, 3, 4 and 5, equally spaced on the periphery of a stamping roll 55 which is fixed on a shaft 56 journaled in the outer ends of two spaced carrying arms 57. These arms are fixed to one another and mounted for pivotal movement on a shaft 58 carried by a fixed bracket 59 on the frame 10.

65 A spring 60 connected to the arms 57 normally

70 75 A spring 60 connected to the arms 57 normally

holds these arms in a raised position in which the stamping roll 55 is slightly spaced away from the cylinder block and in this raised position of the arms 57 a drive roller 61 fixed to the shaft 56 engages a friction drive wheel 62 on a shaft 63 which is driven by a belt 64. The several belts of the several marking mechanisms are driven from a common shaft 65 as shown in Fig. 2 from a suitable driving motor 74 shown in Fig. 1. The shaft 63 is carried by an arm 66 pivotally supported on the stationary bracket 59 as will be apparent from Figs. 4, 5 and 7.

It will be understood that the continuously driven friction wheel 62 rotates the stamping wheel 55 continuously until the stamping wheel is stopped and this occurs when teeth 67 on the wheel 61 are engaged by a pawl lever 68 pivotally carried at 69, see Fig. 5, and yieldingly urged counterclockwise by a spring 70. Normally the spring 70 is overcome and the pawl 68 is raised from the teeth 67 by means of the spring 60 which holds a link 71 lowered and engaged with and depressing the projecting end of the pawl lever 68. Spring 60 is overcome when an electromagnet 72 is energized and this takes place at the proper time in the gauging cycle so as to raise the link 71 which is connected to the armature 73 of the electromagnet, thus permitting the pawl 68 to be lowered by spring 70 into engagement with the proper depression of the stop wheel 67 which is thus arrested, stopping the rotation of the stamping wheel so that the proper numeral is facing the adjacent surface of the cylinder block. Having been properly located as will be further described, a hammer blow is applied to the marking wheel by a hammer or plunger 75.

The selection of the proper character or numeral corresponding to the gauged dimension classification of the cylinder bore is effected as follows: A fixed insulated ring 76 carried by arms 57 is provided with a series of electric terminals 77 equally spaced and corresponding in number to the number of individual characters or numerals on the stamping wheel, in this case five in number. Each terminal is adapted to be successively contacted by a wiper contact 78 on a flexible disk segment 79 which is carried by conductor ring 80 the periphery of which engages a contact brush 81 through which current is supplied to the gauging circuits as will be further described in connection with the wiring diagram. The wiping contact 78 rotates with the marking wheel and the arrangement is such that one of the five contacts 77 is energized at the proper time in the sequence of the gauging operation. If the size range of the cylinder bore is classified No. 2 for example, then the No. 2 contact of the terminals 77 will be energized and as soon as the wiping contact 78 reaches it a circuit is closed through the solenoid 72 energizing the solenoid and moving the armature 72 upwardly as viewed in Fig. 5, bringing the stop pawl 68 against the proper notch to stop the stamp wheel so that the No. 2 character is facing the upper side of the cylinder block. Shortly after the wheel 55 is stopped a blow is struck on the plunger or hammer 75 so as to move the marking wheel downwardly about the shaft 58 which carries the arms 57, so that the raised numeral on the marking wheel is indented in the cylinder block which is thus classified in accordance with the particular diameter. After the stamp is applied, the spring 60 pulls the marking wheel up away from the cylinder block 75

when the solenoid 72 is subsequently deenergized at the proper time in the gauging sequence.

As shown in Figs. 1 and 2, the hammers or weights that strike the plungers 75 are heavy arms 83, one for each cylinder bore, pivotally carried on two spaced supporting shafts 84. Each of these arms 83 is raised to its normal elevated position, after the gauging operation and the marking operation have taken place, by means of a roller 85, one for each arm, and carried by the slide 45 so that as the slide is raised to retract the gauging heads, the levers 83 are raised and after their upward movements have been completed they are latched in raised position by latching arms 86, see Fig. 2, carried by the two shafts 87. At one end of each of the shafts 87 is an operating arm 88 fixed to the shaft and pivotally connected to a link 89. The adjacent ends of the two links 89 are pivotally connected at 90 to a vertically movable piston rod 91 controlled by hydraulic fluid pressure and movable upwardly to the position shown in Fig. 2 so as to move the several latch arms 86 into latched position. At the proper time in the sequence of operation, however, an electric switch controls the fluid supply to the fluid pressure cylinder in which the piston 91 operates so as to depress that piston and move the shafts 87 in opposite direction to release the latch arms 86 and permit the arms 83 to fall and strike the plungers of the stamping mechanism all at the same time.

There is provision in accordance with the present invention, for adjusting the parts of the air gauging system so that the various switches that are controlled by pressure responsive devices may be properly set to give several different classifications with the use of only a maximum and a minimum master instead of having a setting master for each one of the five different classification sizes. Thus in accordance with Fig. 11 air under pressure is supplied through an open shutoff valve 100 and a suitable air filter 101 to two primary pressure regulators 102, one for each side of the gauging apparatus. Each pressure regulator 102 is connected at its outlet side to four secondary pressure regulators 103, one for each gauging head. Connected to each of the pressure regulators 103 at its discharge side is a setting valve 104 and an adjustable restrictor 105, the restrictor being connected to a pressure gauge 106 and to the pressure responsive switches 107 and also to the conduit that supplies the regulated air under pressure to the discharge orifices 52 of the gauging head so that the amount of leakage taking place through the gauging nozzles depends on the clearance between the ends of those nozzles and the cylinder bore. The amount of this flow is indicated by the pressure gauge 106 and also determines the condition of the pressure controlled switches 107. Each of these switches 107 may be of the character disclosed in Patent 2,448,653 granted September 7, 1948. The pressure gauge 106 may be a simple pressure gauge having an indicating needle and a scale having maximum and minimum indication markings and three additional equally spaced lines between the maximum and minimum markings on the scale to provide five different positions corresponding to the five different selections to be obtained. In setting up the apparatus for any particular cylinder bore the contacts of the three switches 107 are adjusted to operate at the particular pressures corresponding to the particular size classifications. In making this adjustment the gauging head is

first moved beyond its normal raised position by manual control of the various control switches of the electrical system until the nozzles 52 are inside the minimum master 109 contained in the master holder 111 which also contains the maximum master 110. With the gauging head in the minimum master 109 adjustments are made in the pressure regulator 103 and the adjustable restrictor 105 until the pressure gauge 106 shows minimum reading, or in other words until the indicating needle is opposite minimum marking on the scale. The gauging head is then moved into the maximum master 110 and adjustments are made if necessary in the setting of the regulator 103 and the restrictor 105 so that the needle of the indicating gauge 106 reads maximum. Having adjusted the settings of the pressure regulator and the needle valve so that the pressure gauge correctly reads minimum and maximum when the minimum and maximum masters are opposite the gauging nozzles and having adjusted the switches 107 to correspond to maximum and minimum sizes, the operator positions the gauging head in the minimum master and partly closes the setting valve 104 to apply an additional restriction in the path of flow from the regulator 103 to the gauging nozzles until the needle of the gauge 106 comes opposite the size 2 classification mark. He then adjusts the switch 107 for the Number 2 classification. Further restriction is then applied by further throttling the flow by controlling the setting 104, still using the minimum master, until the needle of the gauge 106 reads size 3 classification and the switches 107, corresponding to size 3 classification, are then adjusted. This is again repeated to set the gauge for size 4 classification and then the setting valve 104 is opened so that the previously set adjustable restrictor or needle valve 105 will determine the pressure existing at the switches and applied to the pressure gauge and the gauging nozzles under gauging conditions. It will be understood that no adjustment is made in the setting of the restrictor 105 or in the setting of the pressure regulator 103 after adjusting those parts for maximum and minimum master settings with the maximum and minimum masters in place. The addition of a further restriction by throttling the flow through setting valve 104 with the minimum master in place is a temporary expedient employed only during setup to apply proper pressure to pressure controlled switches 107 so they can be adjusted to the particular values obtained for the Number 2, 3, and 4 classifications. The same setup operation is then carried out on the air circuits of the other gauging heads until all of the gauging switches are properly adjusted.

Fig. 10 shows the hydraulic connections of the apparatus. Fluid pressure supplied from a pump 114 connected to a supply tank 115 and operated by a motor 116 which may be contained in the base of the frame 10. Fluid is supplied from the pump 114 to a pressure line 117 and returns to the pump through return line 118. These lines are connected to the feed ram cylinder 22, a clamp cylinder 119 which operates holdown clamp 38, the two left hand cylinders 47 which control the slide 45 holding the gauging heads, the two right hand cylinders 47 for the gauging heads on the other side of the apparatus, the cylinder 35 which controls the locating pin 37 and the trip operating cylinder which controls the piston 91 for tripping the hammer arms 83. Suitable valves are provided in the several hydraulic lines

under the control of solenoids which will be referred to more fully in connection with the wiring diagrams so that these several hydraulic cylinders are supplied with fluid at the proper time for their intended operations.

Reference to the timing chart illustrated in Fig. 12 shows that at the start of the cycle a feeding or loading operation of the traverse ram first takes place and then immediately the locating pin is moved into the work. After the locating pin is in place, the holdown clamp operates and the gauging spindles then start to descend and at the same time they start to descend the traverse ram starts to return to its normal position ready to engage the next cylinder block supplied to the loading plate 11. After the gauging spindles have been lowered the various holding circuits and gauging lamps and indicating lights are energized and a time-delay relay is energized. This time-delay relay starts a sensing period in which the various gauging switches are connected to their respective relays. The selector circuits are then energized in accordance with the gauge results and after a predetermined time interval sufficient for all of the selections to take place, the selector solenoids are all energized and the stamp weights or levers start dropping. At the start of the sensing period various counters which automatically count the gauged cylinder bores of each particular size classification are energized. After the stamping operation takes place, the stamping levers are raised as the gauging spindles are retracted, the clamp and the locating pins are retracted, the selector and holding circuits are deenergized and the apparatus is ready for another cycle.

Current is supplied to the gauging apparatus, as shown in Fig. 13a, from a suitable power source connected through a supply switch 130 to the switches of the hydraulic pump motor 116 and the selector motor 74. A transformer 131 is supplied from the power source and is connected to the main feed lines 132 and 133. With the main supply switch 130 closed, the operator may depress switch 134 and close a circuit through the normally closed stop switch 135 to energize the switch controlling relay 136, the circuit being completed through a manually operable switch 156 a number of which are employed for use during setup operations. In describing the operation, switch controlling relays will be given reference numerals and the switches they control will have the same numeral with a suffix letter. Thus the relay 136 when energized closes a switch 136a so as to apply a holding circuit around the start switch 134. Energizing the relay 136 also closes switch 136b to start the motor 116. This preconditions the apparatus for a gauging operation. The operator then pushes a second start switch 137 preparatory to initiating a complete cycle of operations. Closing this switch 137 completes a circuit through emergency stop switches 138 and through a relay 139 to close holding switch 139a and circuit establishing switch 139b.

Having established operating conditions the operator then closes cycle starting switch 142 completing a circuit to the relay 143 which closes a switch 143a. The circuit through relay 143 goes through a limit switch 144 which is closed until the holdown clamp is lowered, through a limit switch 145 (shown in Fig. 2) which is closed until the locating pin 37 is raised, through a limit switch 146 which is closed until the holdown clamp 38 starts to descend, through a

manually controlled traverse return controlling switch 147, through a normally closed relay controlling switch 213b and through another relay controlled switch 178a which is closed as soon as switch 139b is energized to complete a circuit through relay 178 completed through the limit switches 180 which are closed as long as the gauging head carrying slides are in their raised positions.

When the start switch 142 is temporarily closed a switch 150 is opened to de-energize a relay 151 and open switch 151b to de-energize the holding circuit of the gauge relays that may have been closed from a previous cycle.

When relay 143 is energized it also closes switch 143b to complete a circuit through a solenoid operated hydraulic valve 153 which controls the traverse ram cylinder 22 illustrated in Fig. 10. This permits a supply of hydraulic fluid to move the rod 21 and pull the cylinder block into gauging position. At the completion of the travel of the cylinder block the pivoted lever 30 is moved counterclockwise by the block and actuates a limit switch 154. This energizes the lead line 155 and current is supplied through the normally closed manually operated switches 156, to energize a relay 157 which closes switch 157a to energize hydraulic valve 158 which controls flow to the locating pin cylinder 35. This causes the locating pin to be raised. When the locating pin is raised, the arm 36 releases the switch 145 and permits it to open but a circuit continues through relay 143 around through the holding circuit switch 143a. However, the time this switch 145 opens is not important.

When relay 157 closes it also energizes holding switch 157b and a switch 157c. When the locating pin 37 is fully raised it closes limit switch 159 to complete a circuit through the clamp relay 160 which energizes a solenoid operated hydraulic valve 161 which initiates downward movement of the holdown clamp 38. Relay 160 also closes a hold-in circuit through switch 160b. As soon as the clamp starts to move down it opens the limit switch 146 and here again the time of opening is not significant. When the clamp is fully lowered it closes limit switch 162 and opens switch 144 to deenergize relay 143 and deenergize the solenoid valve 153 permitting return travel of the traverse ram ready to pick up another cylinder block. Return movement of the traverse ram opens the limit switch 154 which it controls and deenergizes the line 155 but this does not deenergize relays 157 or 160 which are supplied from the line side 132 through normally closed switch 151a controlled by relay 151 which is not energized.

When the switch 162 closes it energizes a line 163 which supplies current through normally closed and manually operable switches 164, 165 and 166 energizing line 167, limit switches 169 and 170, 171, 172, line 173, relay controlled switch 175a energizing relay 176. When the relay 176 is energized as just described, it closes switch 176a energizing solenoid operated hydraulic valve 177 to supply fluid to the cylinder 47 of the right hand bank and lower the slide that carries the gauging heads. At the same time a similar circuit is completed through a relay 179 to lower the left hand bank of gauging heads, energization of relay 179 closing relay 179a and energizing the solenoid valve 180 for this purpose.

As soon as the slides carrying the gauging heads start down they open the limit switches 180 deenergizing relay 178. Deenergization of re-

lay 179 thus further conditions the circuit through the relay 143 for a subsequent operation. Upon full descent of the gauge head slides the limit switches 181 and 182 are automatically closed to energize relay 183. This relay closes switch 183a to complete a circuit through a normally closed manually operable switch 184 through relay 151 and simultaneously energizes a time-delay relay 185. Energization of relay 151 closes switch 151c and also closes a switch 151d so associated with switch 151a as to close before switch 151a opens. This transfers the energization of relays 160 and 157 to line 187 through closed switch 151d, since switch 151a which now opens would otherwise deenergize those relays. Energization of the time-delay relay 185 closes switch 185a completing a circuit through closed switch 150, switches 183a and 184 and a closed time-delay switch 187a and energizes relay 188. This connects the gauge head switches to the gauge relays by closing switches 188a to 188f inclusive.

The several switches 188a to 188f complete circuits through relays 190 to 195 inclusive depending upon the operation of the gauge head controlled switches 107 which are controlled in turn by the air pressure supplied to those switches. The switches 107 operate to divide the acceptable size range into five different classifications as will be further described. At this point it is mentioned that these relays 190 to 195 control circuits which energize only one of the five contacts 77 of the marking head to energize relay 210 closing switch 210a to energize the solenoid 72 of the marking mechanism at the proper time to stop rotation of the marking head when the selected numeral is facing the cylinder block. It should also be understood that only one marking mechanism for one cylinder is illustrated in the wiring diagram and that a complete wiring diagram would include similar circuits for each of the other seven cylinders.

It should also be understood that prior to energization of this solenoid 72, the motor 74 which operates the drive belts for the several marking mechanisms had been started by closing control switches 140a through energization of relay 140 due to switch 183b closed by energization of relay 183 having taken place when the limit switches 181 and 182 closed as previously described.

The electrical switches 107, see Fig. 13b, may be of the character disclosed in Patent 2,448,653, these being provided in groups of three for each cylinder bore and with each switch controlling two contacts both of which are closed if the dimension gauged is within a predetermined size range for which the contacts have been adjusted, the size range settings being different for the different switches so that five different selections are obtained within the limits of permissible maximum and minimum tolerance limits. One of these switches as shown in Fig. 13b is provided with contacts 196 and 197 connected respectively to relays 190 and 191. If the contacts 196 and 197 are both closed relays 190 and 191 are energized thus closing switches 190a and 191a and completing a circuit to contact Number 5 of the contacts 77 of the marking mechanism. At this time switch 192a remains closed this switch being controlled by relay 192 which remains open as the blade of this switch 107 is not closed. Thus switch 192b also remains open so that none of the other contacts 4, 3, 2 or 1 can be energized. As soon as the contact 78

of the rotatable wiping brush 79 reaches contact 5, a circuit is closed through lead 198 to energize the relay controlling solenoid 210 as previously mentioned. If for example the dimension of the bore is such as to fall in the Number 1 classification so that contact Number 1 would be energized, then all the contacts 196, 197, 200 and 202 of the switches 107 would be closed except the blades 199 and 201 which would be open. Thus relays 193 and 195 would not be energized but the other relays 190, 191, 192 and 194 would be energized to open switches 192a and 194c and keeping switches 195b and 193b closed so that current flows only to contact Number 1. Then it is only when the wiping contact 78 reaches contact Number 1 that a circuit would be completed through lead wire 198 to energize the solenoid controlling relay 210. Contact Number 2 would be energized corresponding to a Number 2 classification when relay 193 is energized by closing contact 199 thus opening switch 193b to interrupt the circuit to the Number 1 contact and closing switch 193c to complete a circuit to the Number 2 contact, relay 195 remaining open and relays 192 and 194 being closed since they are connected in circuit through the closed blades of their respective switches 107.

Relays 190 to 195 also control switches 190d to 195d and 190e to 195e respectively to operate signal lamps 1 for the respective relay circuits.

As contact Number 1, for example, is energized and even prior to contact 78 reaching it, the wire 204 is energized to supply current through a counting circuit which is generally designated 205. There is an individual control wire for each of the five contacts of each of the eight different cylinder bores. The eight individual wires leading to the eight Number 1 classification circuits of the eight cylinder bores are all connected to one bank of a stepping relay having a wiping contact 206, which successively operates along all of these eight terminals and if all eight of them are energized it would produce eight steps in a Number 1 classification solenoid counter 207. In a similar manner, a stepping relay circuit and solenoid counters are provided for each of the other classifications. The stepping relay includes contacts 208 all of which must be successively passed over by a wiping contact 209 in any counting period before energization takes place of the relay 212. At the completion of the counting cycle when relay 212 is energized it opens switch 212a to deenergize the relay 213 and thus open a switch 213a which must remain closed for the duration of the counting cycle but open thereafter.

The stepping action of the stepping relay is effected by rectifier 215 supplying D.-C. current to circuits 216 for proper energization of a power solenoid 217 which furnishes power to move the wiping contacts through a complete cycle. Since the detail construction of the stepping relay is of no particular significance, a more detailed description seems unnecessary.

It has already been described how time-delay switch 185 closed to initiate connection of the gauge heads to their gauge relays. At the same time this occurred a circuit was completed through lead wire 230 to energize timer switch 187 which after a time delay closes switch 187b and opens switch 187a. Closing 187b energizes relay 231 to energize the selector circuits that effect the marking. This is accomplished by

closing switch 231a supplying current from the line side 132 to the marking mechanism circuits.

If all of the cylinders fall within the required tolerance range the switch contacts 196 and 197 are both closed and a relay 232 will be energized, such relay being provided in each selector circuit for each bore. One or the other of the relays 190 or 191 will be deenergized if any cylinder is outside the tolerance range and in such event no current will be supplied through the switches 190a or 191a and no current flows to the relay 232. Within tolerance limits, however, relay 232 will be energized so that the counting operation can take place. The eight relays 232 when energized close their eight respective switches 232a, see Fig. 13c, and energize relay 233 and when relay 233 is energized it closes the energizing switch 233a of the counting stepping relay, otherwise this relay would not operate. Furthermore unless some one of the contacts of each of the five marking contacts 77 are energized no current will be supplied through lead wire 192 to the relay 210 and the further sequence of operation will stop. The operator will then close switch 235 to cause 25 the gauge heads to be retracted which in turn causes the clamp and the locating pin to be released or withdrawn.

It has been mentioned that relay 210 is energized when the proper numeral on the stamp mechanism has been selected for a particular cylinder. There are seven additional relays, one for each of the other seven bores of the cylinder block, and each of these relays controls individual switches 210d arranged in series, as shown 30 in Fig. 13b, to complete a circuit after all of the selecting circuits of the marking devices have been energized, through a relay 236, and also through a timing switch relay 237. Closing of relay 236 energizes a switch 236a to energize a solenoid 35 operated hydraulic valve 238 which controls the tripping cylinder to lower rod 91 and trip the weight arms so that all of the marking wheels are simultaneously struck through their operating pins 75 and the several classifications of the different cylinder bores are simultaneously applied to the cylinder block.

Energization of the timer relay 237 closes switch 237a to insure continued energization of the selector circuits and act as a hold-in for the 50 relays 151 and 185. After a time delay sufficient for the hammer weights to drop the energization of time-delay relay 237 closes switch 237b to energize relays 240 and 241 to close switches 240a and 240b, thus energizing solenoid operated hydraulic valves 242 and 243 which admits hydraulic fluid to the cylinder 47 on both sides of the machine and raises the slides that carry the gauge heads so they are returned to normal raised position. As the slides start to move upwardly they open limit switches 181 and 182 to deenergize relay 183, and open switch 183a, although the circuit is maintained through closed switch 151c to the relays 151 and 185. At the 55 upper limit of movement of the gauging head carrying slides, the limit switches 180 are closed again energizing relay 178, opening switch 178b and deenergizing relays 160 and 167 so that the clamp controlling solenoid valve is deenergized to reverse the direction of flow to the cylinder 119 and raise the clamp. Also a reversing of the direction of the fluid supplied to the cylinder 35 takes place to release the locating pin. The limit switches operated by the clamping mechanism and by the locating pin mechanism having

been previously mentioned and these mechanisms return to their normal position because the switches themselves that they control are returned to normal position and condition the several circuits for subsequent gauging operation.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. Gauging means for simultaneously gauging a plurality of bores of a cylinder block comprising a support providing a gauging station for cylinder blocks, means operable to move a block into the gauging station, a plurality of gauging heads on said support, means controlled by said heads and including fluid pressure controlled switches, means operable to simultaneously move the heads into gauging engagement with the bores of the block, each of said heads having a leakage orifice which determines the pressure applied to the switches in accordance with the gauged dimensions of the bores, a marking stamp for each of said heads each having a plurality of indicia movable to a predetermined marking position, means controlled by said pressure switches for selecting the proper indicia in accordance with the dimensions gauged by said heads, means for automatically operating said marking stamps at a predetermined time in a gauging cycle for simultaneously applying the selected indicia to the gauged block, maximum and minimum masters selectively engageable with each of said heads, a pressure gauge connected to the fluid pressure controlled switches and having indicia corresponding to the maximum and minimum masters and additional indicia therebetween, and means for temporarily adjusting the pressure to which the switches are subjected when one of the masters is engaged with the head for setting adjustment of the switches to operate at pressures between the values corresponding to the maximum and minimum masters.

2. A gauging apparatus for simultaneously gauging a plurality of bores of a cylinder block, comprising a support providing a gauging station for the cylinder block, means operative to move a cylinder block into the gauging station, means for definitely fixing the block in a predetermined gauging position in the gauging station, a plurality of gauging heads carried by said support in a normally retracted position, means operable to simultaneously project the heads into the cylinder bores of the block, a marking stamp for each of said heads having a plurality of indicia movable to a predetermined position, means controlled by each of said gauging heads for selecting the proper indicia on its respective stamp in accordance with the dimension gauged by said head, weight members operable to strike said stamps, and means operable automatically at a predetermined time in a gauging cycle for causing operation of the weight members to apply the selective indicia to the article.

3. A gauging apparatus for simultaneously gauging a plurality of bores of a cylinder block comprising a support providing a gauging station for the cylinder block, means operative to move a cylinder block into the gauging station, means for definitely fixing the block in a predetermined gauging position in the gauging station, a plurality of gauging heads carried by said support

in a normally retracted position, power means operable to simultaneously project the heads into the cylinder bores of the block, means for automatically stopping said power means to stop the movement of said heads when any head is prevented from entering a cylinder bore, a marking stamp for each of said heads having a plurality of indicia movable to a predetermined position, means controlled by each of said gauging heads for selecting the proper indicia on its respective stamp in accordance with the dimension gauged by said head, weight members operable to strike said stamps, and means operable automatically at a predetermined time in a gauging cycle for causing operation of the weight members to apply the selective indicia to the article.

4. A gauging apparatus for simultaneously gauging a plurality of bores of a cylinder block comprising a support providing a gauging station for the cylinder blocks, means for definitely fixing the block in a predetermined gauging position in the gauging station, a plurality of gauging heads carried by said support in a normally retracted position, means operable to simultaneously project the heads into the cylinder bores of the block, a marking stamp for each of said heads having a plurality of indicia movable to a predetermined position, selecting means controlled by each of said gauging heads for selecting the proper indicia on its respective stamp in accordance with the dimension gauged by said head, counting means controlled by said selecting means for counting and totalizing the number of gauged holes individually in each size classification, means operable to strike said stamps, and means operable automatically at a predetermined time in a gauging cycle for causing operation of the last named means to apply the selective indicia to the article.

5. A gauging apparatus for simultaneously gauging a plurality of bores of a cylinder block comprising a support providing a gauging station for the cylinder block, means for definitely fixing the block in a predetermined gauging position in the gauging station, a plurality of gauging heads carried by said support in a normally retracted position, means operable to simultaneously project the heads into the cylinder bores of the block, a marking stamp for each of said heads having a plurality of indicia movable to a predetermined position, means controlled by each of said gauging heads and including fluid pressure controlled switches, each of said heads having a leakage orifice which determines the pressures applied to the switches in accordance with the gauged dimensions of the cylinder bores, means controlled by said switches for selecting the proper indicia on the marking stamps in accordance with the dimensions gauged by its respective heads, means operable to impress the stamps on the cylinder block, and means for timing the operation of said projecting means, gauging means and marking means to automatically produce predetermined sequential operation thereof.
